UNITED STATES PATENT OFFICE.

JAMES E. JONES, OF WASHINGTON, DISTRICT OF COLUMBIA.

HOLDING AND SERVING DEVICE FOR TOILET-SEAT COVERINGS.

Application filed September 7, 1922. Serial No. 586,580.

To all whom it may concern:

Be it known that I, JAMES E. JONES, a citizen of the United States, residing at Washington, District of Columbia, have invented certain new and useful Improvements in Holding and Serving Devices for Toilet-Seat Coverings; and I do hereby declare the following to be a full, clear, and exact description of the invention, such as will enable others skilled in the art to which it appertains to make and use the same.

The object of my invention is the provision of a device or means for normally securely holding in place superimposed layers of toilet seat coverings, generally consisting of sheets of paper cut to the required shape, said device having a spring or springs which press the sheets towards the opening therein, and a push bar or rod or button for compressing the spring or springs so the layers of the paper may be loosened enabling the operator to withdraw the top sheet of the layers without displacing any of the sheets beneath.

A further object is the provision of a device of this character which will maintain the layers of paper in a sanitary condition, free from dust and dirt, and prevent the waste of paper by the withdrawal of an unnecessary number of sheets.

The invention consists in certain novelties of construction and in the combination of parts as herein set forth and specified in the claims.

The accompanying drawing illustrates an example of the embodiment of the invention, the same being constructed and the parts combined according to the best mode of procedure I have so far devised for the purpose.

Figure 1 is an elevation view of an ordinary toilet appliance with my improved holding and serving device hinged to the flush tank.

Fig. 2 is a front elevation view of the holding and serving device with the layers of paper removed, showing in dotted lines the rods or bars secured to the under surface of the pressure plate.

Fig. 3 is a cross section in elevation of Figure 2 taken on line 3—3, with the sheets of paper in place.

Fig. 4 is a vertical section in elevation of Figure 2 taken on the line 4—4, with the sheets of paper in place.

The body of the holding and serving device may be made of any suitable material, wood or metal, but preferably of sheet metal stamped or pressed to the required shape, though it may be made of fashioned parts 60 united by solder or rivets.

Referring to the several figures, the numeral 1 designates the base or bottom position of the shape shown; 2 the curved side wall disposed at right angles to the base; 65 and 3 the inwardly turned edge of the wall. The edge of the metal is cut away at 4 to permit the thumb and finger to grasp and withdraw the top sheet of paper when the layers are loosened from spring pressure.

At the center of the base is a projecting portion 5 secured to the base by solder or otherwise, and the shape is approximately as shown. In the vertical wall thereof are four slots 6 and the top surface has a hole 70 7 for the push rod, bar or button. The numeral 8 designates the pressure plate loosely disposed within the interior of the body portion of the device; 9, coiled springs pressing the plate towards the opening at 80 the top; 10, the push rod, bar or button projecting above the top surface of the portion 5, as shown; 11, rods or bars secured to the lower end of the push rod and extended loosely through the slots 6 to the lower surface of the pressure plate; and 12 are downwardly bent portions of the metal of the pressure plate providing openings through which the ends of the rods or bar 11 pass 85 where they may be secured by solder or otherwise.

The holding device may be supported in any desirable way in any convenient location. It is shown supported upon the flush tank by a hinge 13 and a catch 14. This 90 arrangement allows the device to be swung out of the way when the space is limited so the cover and seat may be raised. Other modes of supporting the device on a flush tank may be selected, depending upon the 100 type of flush tank used and its location relative to the seat.

The layers of paper 15 are shown by Figures 3 and 4 arranged parallel and in contact with the top surface of the pressure plate, the inwardly turned edge 3 holding the paper in place adjacent the top opening when the pressure plate and layers of paper are under spring pressure. Downward pressure upon the push rod 10 contracts the 110

springs and loosens the mass of paper so the edge of the outer sheet can be grasped by the thumb and finger and withdrawn without displacing the sheets beneath.

5. From the foregoing description taken in connection with the drawing, it is clear that I have provided a device of the character described which is simple in construction, efficient in operation, cheap in first cost, and 10 which fulfills all the conditions set forth as the object of the invention.

What I claim is:

1. The combination in a holding and serving device of a hollow container with a vertical wall, for receiving sheets of paper, said container being substantially open at one side; a movable pressure plate within the container; spring means for pressing the said plate towards the open side; means at 15 the edge of the vertical wall to hold layers of paper parallel with the pressure plate and within the container; and means for moving the pressure plate downwardly and 20

loosening the sheets of paper above the plate so one sheet may be withdrawn.

2. The subject-matter of claim 1 with the addition of a central projecting portion 5 for holding the inner edges of the sheets of paper in parallel relation to each other.

3. The subject-matter of claim 1 wherein 30 the means for holding the layers of paper parallel with the pressure plate and in the container comprises the turning inwardly of the edge of the vertical wall.

4. The subject matter of claim 1 wherein 35 the means for moving the pressure plate downwardly consists of a push rod, bar, or button connected with the pressure plate.

5. The subject-matter of claim 1 with the addition of a projecting portion 5 which is 40 provided with guiding slots for the reception of rods forming part of the means for moving the pressure plate downwardly and loosening the sheets of paper.

In testimony whereof I affix my signature.
JAMES E. JONES.
